UNITED STATES PATENT OFFICE

FRANK P. J. STRUCKMEYER, OF SAN FRANCISCO, CALIFORNIA

WINDOW CONSTRUCTION

Application filed May 4, 1931. Serial No. 534,726.

This invention relates particularly to a double hung window sash construction wherein the individual sash may be opened inwardly for more effective ventilation, or to facilitate the cleaning of said sash.

An object of the invention is to provide in a window having sliding sashes therein, means whereby either one or both of the sash may be entirely removed from the inside of 10 the window opening, or the said sash may be swung into any desired angular position relative to the opening.

Other objects and advantages are to provide a double hung window sash construction 15 that will be superior in point of simplicity, inexpensiveness of construction, positiveness of operation, and facility and convenience in use and general efficiency.

In this specification and the annexed drawing, the invention is illustrated in the form considered to be the best, but it is to be understood that the invention is not limited to such form, because it may be embodied in other forms; and it is also to be understood that 25 in and by the claims following the description, it is desired to cover the invention in whatsoever form it may be embodied.

In the accompanying one sheet of drawing:

Fig. 1 is a cross sectional view of the window constructed in accordance with my invention.

Fig. 2 is a cross sectional view of the window showing the removable jamb portions and one of the sash removed from the window opening.

Fig. 3 is a vertical section of the window frame of my construction, without the sash, the section being taken on the line 3—3 of Fig. 1.

Fig. 4 is a perspective view of the telescopic mounting mechanism for the removable jamb sections.

Fig. 5 is a telescoping mounting means in an operative position.

Fig. 6 is a sectional detail view taken on the line 6—6 of Fig. 1.

In detail the construction illustrated in the drawing comprises a window frame formed of the side jambs 1 on opposite sides 50 thereof, the overhead lintel 2, the stool and

sill 3 and 4 at the bottom of the frame, and the casing 6 around the inside and outside of the frame. The sashes 7 and 8 are mounted to slide past each other in a vertical direction within the frame, the said sashes being 55 separated by a parting bead 9 confined in a groove 10 in the said jambs and lintel. A stop strip 11 extends around the inside of the edge of the jambs and lintel, and a similar stop 12 around the outside of the frame, each of 60 said stops lying parallel to the parting bead to provide guideways in which the opposite side edges of the window sash are free to slide. A sash pulley 13 is arranged adjacent the upper end of each sash track, and a sash 65 cord 14 mounted on the side of each of the sashes passes around the sash pulley, and the unsecured end of the said sash cord is provided with a sash weight thereon mounted on the rear of the jamb 1. The sash weights 70 15 counterbalance the weight of the sash, and thereby minimize the amount of effort required to move the sash in a vertical direction either upwardly or downwardly. The construction thus far described, is conventional to what is known as a double hung 75 sliding window.

In adapting my invention to a double hung sliding sash, I cut away a portion of the face of each jamb, facing the window opening, in 80 a horizontal direction from the edge of the jamb on the inner side thereof to a point substantially flush with the outer side of the parting bead, and in a vertical direction for a distance greater than the height of the lower 85 sash. Each of the opposite jambs 1 are cut away as at 16, in like amount, and the cut away portion extends from a point slightly above the stool 3, to a point above the upper stile of the lower sash. The cut away portion in each jamb provides a shoulder 17 at the bottom edge thereof, and a shoulder 18 at the upper edge thereof. Into each shoulder I secure a channel trackway 19, so 90 that the open portion of the trackways face each other, that is to say, the opening in the lower channel 19 on the shoulder 17 faces upwardly, while the open side of the upper channel 19 on the shoulder 18 faces downwardly. Each of the shoulders are arranged 95 100

in alignment and the width of the said channel is equal to the depth of the cut away portion 16 so that one exposed side edge of the said channel lies flush with the face of the 6 sash slideway. Each channel guideway 19 is provided with a slide member 20 therein, said slide member having a pin 21 extending laterally therethrough, and the ends of said pin are confined in slots 22 cut in the opposite 10 side walls of the channel. The length of the slots 22 regulates the length of movement of the pin 21 therein, and thereby determines the amount of sliding movement which the slide 20 may have relative to the channel 19. 15 The slide 20 is provided with an extension 23 thereon which conforms in contour in cross section to the slide 20, the extension 23 being pivoted at 24, to the slide 20 so that the extension may pivot or swing on a horizontal 20 plane about a vertical axis relative to the slide 20. Both the slide 20 and extension 23 do not project beyond the open upper side of the channel 19. A filler piece 25 is adapted to be fitted into the cut away portion 16 25 of the jamb, and to fill out the entire area of the cut away portion between the spaced channels 19 and the vertical front and rear edges of the said cut away portion. The opposite ends of the filler piece are secured to 30 the extension members 23 on the opposite slides. The inside face of the filler piece is provided with the parting bead 9 and stop 11 thereon, to form a continuation of the same parts which are a permanent part of 35 the window jamb. When the filler piece is in a position with the bead and stop thereon in alignment with the permanent bead and stop on the window jamb, a slideway is formed for the lower sash which permits said sash 40 to be moved upwardly into a position opposite the upper sash, or to be locked into a permanent position in the lower part of the window frame.

If it be assumed that the sashes were not in 45 the window frame, the filler pieces on the opposite side jambs could be moved inwardly toward the interior of the window frame and then swung in a horizontal position through an arc of 90°, to lie flat against the 50 faces of the casing on the inside of the window frame. The slide 20 is permitted to travel toward one edge of the channel guide 19 until the pivot 24 is in an exposed position.

The extension 23 on the slide will then be 55 free to swing backwardly toward the casing on the frame. Assuming the filler piece to be in its normal closed position and the sash installed in operating position in the window frame, the first operation necessary 60 in order for the operator to move the lower sash out of the window frame, would be to slide said lower sash upwardly a slight distance above the face of the sill 3 so that the upper and lower stiles of the said bottom 65 sash would lie between the opposite ends of

the filler piece 25. The operator then would move the said lower sash forward bodily, which action would cause the opposite filler piece 25 to slide outwardly relative to the jamb. When the filler pieces are moved outwardly as far as they can move, then said filler pieces may be swung away from engagement with the opposite side edges of the sash, leaving the sash in exposed position, supported only by the sash cords 14. In this position, the sash is out of the frame and may be manipulated in any suitable manner for either ventilation purposes, or to permit cleaning of the glass, the insertion of a new pane of glass, or the painting of the outside 80 of the said sash, from the interior of the room.

After the lower sash has been removed from the frame in the manner hereinabove set forth, the upper sash may be slid downwardly to register with the opening provided in the opposite sides of the jamb, and the said upper sash may be bodily removed from the window frame and manipulated as desired. The upper sash may be returned from a position remote from the window frame to the frame by merely shoving it into the opening until opposite sides of the said sash lie in the guideway for said sash. The lower sash, however, is moved into sliding position 95 in the window frame by arranging said sash in a position which is substantially parallel to the position in which it is to be operated, then swinging the filler pieces 25 around so that the guideways therein engage the opposite sides of the sash, and then the sash and filler pieces are forced inwardly into the window frame until the guideways in the opposite sides of the filler pieces register with the corresponding permanent guideways in 100 the window frame.

It is not necessary to lock the filler pieces 25 in position in the jamb, although it is clearly within the scope of this invention to provide locking members on the frame which 110 may be utilized to hold the said filler pieces in a fixed position, until such time as it would be desired to move the filler pieces outwardly in order to remove a sash from the window frame.

For the purpose of illustration, a spring plunger type of lock 26 is shown in the drawing, and especially in Fig. 6.

It is to be noted that by the removal of the fillers and the stops and beads thereon in the aforementioned manner, the usual holes in the casing provided for the removal of the sash weights are rendered easily accessible without necessitating the prying off of the stops. In the usual type of windows the unfastening and removal of the stops before the sash weights can be removed, frequently mars the casing and is in general, inconvenient. This inconvenience is entirely obviated by my structure.

It is also to be noted that instead of cutting away the jamb, a metal filler plate of suitable thickness may be supported on the extension members 23 of the slides. The metal plates would slide on the usual jamb surface and would carry sections of the stops and beads thereon. In this instance the edges of the sashes would be shaved off to a degree to be slidable between the opposed metal 10 filler plates.

Having thus described this invention, what I claim and desire to secure by Letters Patent is:

1. A window including a frame having 15 vertical ledges to afford runways; sashes reciprocating in said runways; telescoping means on the opposite sides of the window to removably support opposed portions of said ledges; portions of said telescoping means 20 being hinged to swing the removable ledge portions into and out of way position, after the said ledges are simultaneously removed from the runway.

2. A window including a frame formed 25 with runways; sashes reciprocating in said runways; a section of one side of each runway being removable to afford clearance for the removal of said sashes; telescoping connecting means between each of said removable sections and the frame to allow the bodily withdrawals of said sections with one of the window sashes from the runways; a movable sectional support forming the movable part of said telescoping connection, the sections thereof being pivotally secured to each other, the said removable sections of the runway side being mounted on the said pivoted support sections whereby they are swingable outwardly away from the respective 30 sides of the sash to allow the free swinging of the window sash.

3. In a window the combination with a 35 casing defining a window opening, upper and lower sash members, inner and outer stops and beads between the stops to form runways for the sash members; of opposed sections in the inner runways being removable inwardly with respect to the wall in which the window casing is mounted; a channel track- 40 way secured to the casing opposite each end of each removable section, so as to be flush with the bottom of the respective runways; a slide member telescoped into each channel with freedom of limited sliding movement 45 inwardly from the window opening; a pivoted element on each of said slide members on which the said removable sections are mounted, whereby the said sections are swingable 50 in an out of way position relatively to said window opening.

In testimony whereof, I have hereunto set my hand at San Francisco, California, this 18th day of April 1931.

FRANK P. J. STRUCKMEYER.
